Application November 18, 1931, Serial No. 575,889
In Great Britain November 22, 1930

13 Claims. (Cl. 101—3)

This invention relates to presses. While the invention is illustrated with reference to a press for smooth plating and embossing operations upon hides and skins, it is to be understood that the invention and various important features thereof may have other applications and uses.

It is an object of this invention to provide a press of the mechanical type having a simple, durable and highly effective mechanism for causing relative movement between the pressure applying members of the press.

To these ends and in accordance with an important feature of the invention the illustrated machine is provided with improved means for causing pressure applying operations between two platens, the illustrated means comprising a pair of eccentrics arranged to operate in peripheral rolling contact with each other, whereby a relatively wide space may be provided between the two platens while they are in separated work receiving position to facilitate introduction of the work and whereby relative movement between the platens in a direction to effect a pressure applying operation takes place rapidly thereby contributing greatly to the efficiency of the press. By employing two co-operating eccentrics of the same or similar contour and size the power of the press, as well as its speed of operation, becomes one of its notable characteristics.

While in the illustrated embodiment of the invention platens are employed as the work treating instrumentalities, it will be understood that the latter are not necessarily of the platen type.

Improved means is provided in the illustrated construction for supporting and driving the co-operating eccentrics comprising shafts on which the eccentrics are fixedly mounted and, secured to the shafts, a pair of intermeshed eccentric gears each of substantially the same eccentricity as that of its associated eccentric. By this construction the shaft for supporting and driving one of the eccentrics may be driven from the shaft supporting the other eccentric although in the operation of the press the shafts are moved toward and from each other to the same extent as are the platens, operating connections between the shafts being maintained by the eccentric gears.

These and other important features of the invention and novel combinations of parts will now be described in detail and then pointed out more particularly in the appended claims.

In the drawings,

Fig. 1 is a front elevation, partly in section, of

a press illustrating one embodiment of the invention;

Fig. 2 is a transverse sectional elevation thereof;

Fig. 3 is an end elevation, partly in section, of the press shown in Fig. 1;

Fig. 4 is a detail of a modification hereinafter referred to;

Fig. 5 is a part-sectional end elevation of a modification illustrating a special mounting for the lower platen, the latter being shown in the operative or pressing position;

Fig. 6 is a view similar to Fig. 5 but shows the platen in inoperative position; and

Fig. 7 is a sectional view along the line VII—VII of Fig. 1 showing adjusting means for the lower platen.

In the illustrated press, specially designed for smooth plating and embossing pieces of leather, there is provided a frame comprising a group of horizontal and parallel beams or girders 1 of I-section, mounted on base members or feet 2, and end members 3 mounted on the top of the beams or girders 1. There are also another similar set of beams or girders 4 mounted on the top of the end members 3, and bearings 5 mounted on the top of the upper beams or girders 4 for a purpose hereinafter mentioned, the whole being rigidly clamped together at opposite ends of the machine by means of vertical bolts 6 and nuts 7.

This machine has platens 8 and 9, the top platen 8 being attached face downwards to the upper group of beams or girders 4 below the same, by screws 10 (Figs. 2 and 3), although nut and bolt or equivalent fastenings may be employed. As clearly shown, a substantial layer or packing 11 of asbestos is interposed between the upper set of girders 4 and the back of this platen 8, said layer or packing being thicker in the center than at the ends to allow for slight deflection of the platen. This platen is furnished with a steam chamber comprising one or more passages or compartments 12 (Fig. 2) for steam, appropriate connections, such as pipes 13 (Fig. 1), being provided between the platen 8 and a suitable source of heat supply. As shown, the heated platen is insulated from the beams by the aforesaid packing 11.

Conveniently, the lower platen 9 is mounted adjustably in a hollow frame or casing comprising separate superposed sections 14 and 15 (Fig. 2), respectively, furnished with a series of half bearings 16 and 17 extending lengthwise thereof for the reception of eccentric or cam shafts 18 and 19 on each of which two or more counteracting eccentrics or cam members 20 and 21 are fas-

5

35

40

45

55

tened, the number of cam members being varied according to the length of the platens. It will be noted that the shafts 18 and 19 receive support at a plurality of points, whereby the pressure is advantageously distributed and the tendency of the shafts to bend unduly is eliminated. The lower half or section 14 of this frame or casing is fastened on the top of the lower group of beams or girders 1 by means of screws 22. The upper section or half 15 which carries the platen 9 is slideable vertically in relation to the lower section, and to this end is fitted within guides constituted by side and end plates 23, 24 attached to the lower section 14. The eccentric or cam shafts 18 and 19 are also furnished respectively with eccentric toothed gears 25, 26 (Fig. 1) whereby the upper shaft 19 is driven from the lower shaft 18 during operation of the cam members 20 and 21, the gears having the same eccentricity as the eccentrics. The construction and arrangement is such that, when the parts are assembled, the eccentric or cam shafts 18 and 19 are superposed parallel with each other with the eccentrics or cams 20, 21 peripherally opposed, contactually with each other, i. e. in rolling engagement, and with the gears 25 and 26 constantly in mesh. The arrangement of eccentrics in rolling contact with each other presents distinct advantages due to reduction of parts to a minimum number and to increased efficiency because of the slight friction encountered while the eccentrics roll upon each other. The purpose of the interposed blocks 27, when provided, is to distribute the pressure exerted during the pressing action over a larger area.

The two sections 14 and 15 of the hollow frame or casing and the side and end plates 23 and 24 form a box-like structure in which the said operating mechanism is practically totally enclosed except for openings 28 at the ends (Fig. 1), to permit ingress and egress of air as the platen moves up and down. When the lower shaft 18 is driven the platen 9 is of course moved up or down in relation to the upper platen 8 by reason of the direct action of the opposed co-acting eccentrics or cams, the maximum pressure being applied when the full extent of the throw or lift of said members is reached. The construction and arrangement of the various parts is such that when the platens are closed the pressure applied by the eccentrics or cams is central so that leather of varying thickness has the same pressure on the thick parts as on the thin parts, as the platens and the point of contact of the eccentrics or the cams with each other or with the interposed block or blocks form a pressure triangle which equalizes the pressure along the two edges of the upper platen. In other words the pressure is equally distributed on the work since the pressure is centrally applied and since a slight tipping movement is permitted between the upper platen-carrying section 15 and the lower section 14. Since the gears are eccentric they remain in mesh irrespective of the movement of the platen 9 and thereby maintain a definite relation circumferentially between the cams or eccentrics.

The lower half or section 14 of the platen frame conveniently serves as an oil reservoir to provide ample and continuous lubrication for the lower shaft, and the bearings for the upper shaft may be lubricated by means of an oil pump (not shown) suitably arranged and driven. The surplus oil from the upper bearing runs down on to the mechanism underneath and collects in the reservoir for use over again.

As will be readily understood the machine is constructed to have a certain amount of yieldability or springiness due to limited deflection of the beams or girders under load, i. e. when the lower platen 9 is raised and pressed against the upper platen 8 by the eccentrics or cams, this being desirable to the production of satisfactory results.

Apart from the aforesaid springiness the platens are also made relatively adjustable by positively operated means to enable the press or machine to deal with work of different thicknesses, and to regulate the pressure applied to the work. Conveniently for this purpose, the lower platen 9 is furnished underneath with oppositely extending inclines or inclined portions 29 and is movably mounted in bearers 30 fixed on the top of the section 15 of the platen frame. Wedges 31 having inclined surfaces complementary to the inclines 29 are slidably mounted in longitudinal guides 32 on the top of said frame section 15 for movement towards and from each other by means of a right and left hand screw shaft 33 operable through the medium of worm 34 and wormwheel 35, or other gearing, also mounted on the section 15 of the platen frame, said gearing being operable by a handwheel 38 located at the front of the machine.

For the purpose of compensating for small inequalities in the material and to give deep embossing, when the machine is used for embossing leather or fibrous materials, the lower platen is covered either with a felt bolster 37, rubber bolster or other resilient material.

A press constructed as aforesaid may be designed for operation by either one or two operators according to the dimensions of the press and the nature of the work to be done.

According to a modified construction, shown in Figs. 5 and 6, and designed to facilitate operation of the press by a single operator, the lower platen 9a and the upper eccentric or cam shaft 19a are mounted on or in a frame 15a carried between arms 38 in turn mounted so as to swing up and down about a horizontal axis 39 constituted by a spindle arranged parallel with the eccentric shaft 19a at one side of the center thereof. This spindle 39 is mounted in bearings 40 fixed on a longitudinal frame member 41 attached to brackets 42 in turn applied to the end members 3 of the machine frame at the front. The lower eccentric or cam shaft 18a is carried in suitable bearings 16a in a separate frame or housing 14a fixed on the lower beams or girders 1. The arrangement is such that in pressure-applying position the platen 9a occupies a horizontal position, as shown in Fig. 5, and, when in work-receiving position, it assumes a steeply inclined or tilted position, as indicated in Fig. 6, so that, when the operator lays the material to be operated upon on the platen 9a, said material will, by slipping down the slope, spread itself over the platen without having to be pulled into position from the back of the machine, the necessity for an assistant operator being thereby eliminated. Preferably and as shown the swinging frame or casing 15a is itself pivoted at 43 on the swing arms so as to enable it to rock transversely to a limited extent, and compression springs 44, located in pockets 45 in the swing arms 38 are interposed between the frame or casing 15a and the arms 38 on opposite sides of the pivot 43 for the purpose of enabling the platen 9a automatically to align itself with the upper platen 8 when the two are brought into contact so that the pres-

sure is distributed uniformly. Stop screws 46 are provided on the frame 15a on opposite sides of the pivot 43 for engagement with the swing arms to limit the rocking movement, said screws being 5 adjusted so as to permit of the maximum movement likely to be required. Any other suitable arrangement may be adopted for the purpose aforesaid.

The machine or press is furnished at one end 10 with driving mechanism including conveniently a clutch shaft 47 from which the lower eccentric or cam shaft 18 or 18a is driven by means of gears 48 to 51 (Figs. 1 and 3) and a flexible coupling 52 (the positions of gears 48 and 49 being indicated 15 in dot and dash lines in Fig. 3), a half cycle stop motion device being provided, conveniently in association with the gearing, automatically to throw out the clutch 53 and thereby arrest the rotation of the eccentric or cam shafts 18 and 19, 20 both when the platens are fully closed. This device comprises a disc 54 furnished with diametrically opposed notches 55 (Fig. 3), and a pivoted lever 56 fitted with a roller 57 for engagement with the disc 54 and connected with a 25 clutch lever 58 through a rod 63. The said lever 56 is also connected with a starting handle 59 through the rod 63, upon operation of which the said roller is withdrawn from one or the other of the aforesaid notches and at the same time the clutch lever 58 is moved against the action of a 30 spring 60 to throw in the clutch. As soon as the machine starts the operator releases the starting handle 59 so that the clutch is held in action by reason of the engagement of the roller with a 35 high part of the disc 54 until the opposite notch comes round. For stopping the machine or press in any intermediate position in case of emergency the following arrangement is provided. Between the clutch lever 58 and the half cycle stop lever 56 40 there is a releasable connection constituted by a catch or bolt 61 slidable in or on an arm 62 of the clutch lever 58. The rod or link 63 is connected to the stop lever 56 at 64 and is furnished with a step or collar 65 for contact with the slidable 45 catch or bolt 61. The said rod 63 is connected to or with the starting handle 59 at 66 and the catch bolt 61 is connected with a counterweighted treadle 67 by means of a link 68 pivoted to the catch 61 and connected to one arm 69 of a lever 50 71 pivoted at 70, the other arm of the lever 71 being connected by another link 72, with the treadle 67. When the press is to be operated by one operator, the aforesaid catch or bolt 61 is normally projected for engagement with the step 55 or collar 65 on the rod 63 by the weighted treadle 67 so that when the starting handle 59 is operated the clutch lever 58 is also operated to put the clutch into action, the clutch being then maintained in action by the notched disc 54 as already described. The weighted treadle 67 may be conditioned to hold bolt 61 in operative position with its free end projecting above collar 65 by nuts 65a upon the screwthreaded free end of rod 72 and adjusting said nut to 60 move the upper end of lever 71 to the right, whereby the bolt 61 is moved to the left. To stop the machine independently of the stop motion comprising disc 54, and irrespective of the position of the platen 9 or 9a, the treadle 67 is depressed, 65 which action withdraws the catch or bolt 61 from engagement with the step or collar 65 and thereby releases the clutch lever 58 which is operated under the action of its controlling spring 60 to throw out the clutch. As illustrated, the clutch 70 lever is adapted to apply, at the same time, by

means of a lever 58a, a brake constituted by a band or shoe 58b associated with a flanged portion 58a of the driven member of the clutch, so that motion is more quickly arrested.

In a machine intended for operation by two operators, the same catch or bolt 61 is utilized as part of a safety mechanism designed to prevent one operator from starting the press or machine while another, for example, an assistant working at the back of the machine, has his hands between the platens. To this end said catch 61 is connected with a handle 73 which one operator, e. g. the assistant, is bound to use before the other operator can start the machine. In a practical arrangement the safety handle 73 is located at the 15 back of the machine and is connected by a rod 85 with an arm 74 on the centrally pivoted lever 71 associated with the treadle operated connections described above. A lost motion connection is provided between the treadle rod 72 and the said 20 lever 71 so as to enable the handle 73 to be operated without affecting the treadle 67, and vice versa. Conveniently for this purpose one arm of the lever 71 is fitted with a collar 75 slidable on the rod 72 and the latter is furnished with an 25 abutment constituted by a nut 76 secured after adjustment by a lock nut 77. The safety handle 73 is controlled by a weight on a lever 86 as will be hereinafter described, and, in this case, where-in the machine is fitted for two operators, the 30 catch or bolt 61 is normally held in a retracted inoperative position under the weight action of the lever 86. The arrangement is such that the assistant operator must operate the safety handle 73 in order to hold the catch or bolt 61 35 in operative position, i. e. in the path of the aforesaid step or collar 65, otherwise movement of the starting handle 59 by the operator at the front of the machine is futile.

To enable the starting mechanism and the 40 safety mechanism to be operated from a plurality of points respectively at the front and back of the machine, shafts 79 and 80 (Figs. 1, 2 and 3) are mounted transversely respectively at opposite ends of the machine in the bearings 5 provided on the top of the upper group of beams or girders 4 as previously mentioned herein. The starting handle 59 is keyed on the right hand shaft 79 at the front end together with a lever 81 to which is connected the rod or link 63 which 50 carries the aforesaid step or collar 65 to operate the clutch lever 58. A counterweighted lever 82 is freely mounted on the other shaft 80 at the front end thereof and at the front of the machine and connected with the starting handle 59 by 55 means of a horizontal bar or rail 83. By reason of this connection between levers 82 and 59, it is clear that lever 59 as well as lever 82 is held in inoperative position, and is returned to such position after hand operation, by the weight on 60 lever 82. Similarly the safety handle 73 at the back of the machine is keyed on the left hand shaft 80 at its rear end and, in conjunction with a lever 84 keyed to shaft 80 at its front end, operates the aforesaid centrally pivoted lever 71 65 through the connecting rod or link 85 (Figs. 1 and 2). A counterweighted lever 86, also at the back of the machine, is freely mounted on the right hand shaft 79 at its rear end and connected with the safety handle 73 by another horizontal 70 bar or rail 87. It will be understood that the operative movements of the starting lever 86 and the safety lever 73 take place against the action of the counterweight on lever 86 and that the return movements of the levers are effected by said 75

weight. It is clear, therefore, that the assistant at the back of the machine may move the catch or bolt 61 to operative position using either lever 86 or 73, and that he must do this before the operator at the front of the machine can effect a pressing operation by moving starting lever 59.

As already alluded to herein, the deflection of the beams or girders 1 and 4 under load is utilized to operate an indicator for indicating in terms of 10 tons or other suitable measure the pressure applied to the work. Conveniently I provide an attachment in the form of a frame adapted to be influenced by the deflection of the beams or girders and in conjunction with a multiplying 15 mechanism, for example, a system of links and levers, to transmit the deflection to a pointer working over a suitably calibrated scale. A convenient arrangement for use in conjunction with upper and lower groups of beams or girders comprises 20 upper and lower horizontal bars 88 and 89 shaped as T irons (Fig. 1) and connected by tie rods 90, the bar 88 being located above the upper groups of beams or girders 4 and the bar 89 below the lower group 1, the arrangement being supported 25 by compression springs 91 interposed between the upper bar 88 and the adjacent beams or girders 4. Fixed centrally on the lower group of beams or girders 1 and below the same is a pointer member 92 (Fig. 1) for action upon the lower bar 89, the latter being held up to the member 92 by the aforesaid springs 91. Two brackets 93, furnished respectively with adjusting screws 94, are mounted respectively on the front and rear beams or girders 4 of the upper group, 30 and two shafts 95 and 96 mounted transversely on the adjacent upper bars 88 are furnished respectively with levers 97 and 98 of equal length and with two smaller levers 99 and 100 formed with cupped free ends, steel balls such as 101 35 being interposed between these cupped ends and the heads of the aforesaid screws 94. The said levers are fast on the shafts. A pointer 102 is pivoted at 103 on the upper free end of the lever 98 and extends from the pivot downwards to a suitably graduated scale 104, and is connected, by 40 means of a lever 105 (or extension) on the opposite side of the pivot and a link 106, with the free end of the other lever 97. Any upward deflection of the upper group of beams or girders and downward deflection of the lower group is transmitted 45 through the bars 88, 89 and tie rods 90 to the multiplying mechanism and thence to the pointer, a considerable multiplication of the deflection being achieved. The calibration of the scale may 50 be obtained by means of a hydraulic jack which is used simply as an accessory to obtain the exact equivalent in tons (or other desired measure) of the deflection of the beams or girders at front and back of the machine under different loads, i. e. 55 pressures exerted by the lower platen against the upper platen in the specific constructions hereinbefore disclosed. Thus when operated as aforesaid the pointer will indicate in terms of tons (or other measure) the pressure exerted on the material in any particular operation.

As will be understood the deflection is taken at the center, i. e. between the ends of the beams or girders, since the deflections under light pressure are extremely small, and the two groups of 60 beams or girders are preferably separately connected with the indicating apparatus as in the arrangement just described so that in all cases the deflections are magnified sufficiently to be indicated.

75 When groups of beams or girders are employed

the girders in each group may be interconnected by transverse rods 107 (Figs. 2 and 3).

A flywheel 108 is preferably provided on the clutch shaft 47 for the purpose of assisting the belt or other driving member over the peak load, i. e., when maximum pressure is being applied to the work, maintaining uniformity of motion, and keeping the power required to drive the press as low as possible.

Having described the invention, what I claim as new and desire to secure by Letters Patent of the United States is:

1. In a press, co-operating presser members for applying pressure to pieces of work, means to cause relative approaching and separating movements of the presser members comprising two pairs of eccentrics, the eccentrics of each pair being arranged in rolling contact with each other, and power means located between and closely adjacent to the pairs of eccentrics to effect co-operative movements of the latter.

2. In a press, co-operating presser members for applying pressure to pieces of work, means to cause relative approaching and separating movements of the presser members comprising two pairs of counteracting eccentrics, the eccentrics of each pair being arranged in rolling engagement with each other, and means comprising intermeshed gears located between the pairs of eccentrics to effect co-operative movements of the latter.

3. In a press, co-operating presser members relatively movable between work receiving and work pressing positions with respect to each other, means to cause such relative movement between the presser members comprising a power-driven shaft, an eccentric on the shaft, a countershaft carried by one of the presser members and arranged in parallelism with respect to the first-mentioned shaft, an eccentric carried by the countershaft in position to have rolling contact with the first-mentioned eccentric, and means to drive the counter-shaft from the power shaft whereby the eccentrics are caused to effect relative movement between the presser members.

4. In a press, a stationary presser member, a presser member movable between work receiving and work pressing positions with respect to the stationary presser member, means to move the movable presser member comprising a power-driven shaft, an eccentric on the shaft, a countershaft mounted in the movable presser member and arranged in parallelism with respect to the first-mentioned shaft, an eccentric carried by the countershaft and arranged in rolling contact with the first-mentioned eccentric, and eccentric gears in mesh with each other and mounted fixedly on the shafts whereby the eccentrics are caused to effect movements of the movable presser member.

5. In a press, a stationary presser member, a movable presser member, a movable support for the movable presser member, a shaft mounted in the movable support, a second shaft mounted stationary with respect to the frame of the machine, a pair of eccentric cam members carried by the shafts in rolling contact with respect to each other, and means to drive the shafts whereby said cam members are caused to move the movable presser member and its support alternately toward and from the stationary presser member.

6. In a press, a stationary presser member, a movable presser member, a movable support for the movable presser member, a shaft mounted in the movable support, a second shaft mounted sta-

tionary with respect to the frame of the machine, a pair of eccentrics carried by the shafts in rolling contact with respect to each other, eccentric gears of an eccentricity substantially the same as that of the eccentrics and mounted fixedly on the shafts in meshed relation to each other, and means to drive said second shaft, whereby the movable presser member is moved alternately toward and from the stationary presser member.

10 7. In a press, a stationary presser member, a presser member pivoted to move between work receiving and work pressing positions with respect to the stationary presser member, means to move the movable presser member comprising a shaft, an eccentric on the shaft, a countershaft carried by the pivoted presser member, an eccentric carried by the countershaft in position to have rolling contact with the first-mentioned eccentric, and means to drive both shafts whereby the eccentrics are caused to roll in contact with each other to effect movement of the movable presser member into widely spaced relation with respect to the stationary presser member and then into co-operative relation thereto.

25 8. In a press, a stationary presser member, a movable presser member, a pivoted support for the movable presser member, a shaft mounted in the pivoted support, a second shaft mounted stationary with respect to the frame of the machine, a pair of eccentrics of substantially the same contour and size carried by the shafts with the eccentrics in rolling contact with each other, and means to drive the shafts whereby the movable presser member and its support are moved alternately into widely spaced relation with respect to the stationary presser member and then into co-operative relation thereto.

9. In a press, a horizontal stationary presser member, a movable presser member, a pivoted support for the movable presser member arranged to support the latter at an angle to the horizontal, a shaft mounted in the pivoted support, a second shaft mounted in bearings carried by the frame of the machine, a pair of eccentrics carried by the shafts with the eccentrics in rolling contact with each other, eccentric gears mounted fixedly on the shafts and in meshed relation to each other, and means to drive said second shaft, whereby the movable presser member is moved by a continuous movement to a horizontal position and then into pressing relation with respect to the stationary presser member and subsequently into widely spaced relation thereto.

10. In a press, co-operating presser members for applying pressure to pieces of work, means to cause relative approaching and separating move-

ments of the presser members comprising two pairs of eccentrics, shafts supporting the eccentrics, one of said shafts being power driven, power means located between the pairs of eccentrics to drive the other shaft from the first-mentioned power driven shaft, and bearings for the shafts located on each side of each pair of eccentrics.

11. In a press, co-operating presser members for applying pressure to pieces of work, means to cause relative approaching and separating movements of the presser members comprising two pairs of co-operating eccentrics, the eccentrics of each pair being arranged in rolling engagement with each other, intermeshed eccentric gears located between the pairs of eccentrics, shafts for the eccentrics and eccentric gears, one of said shafts being driven by the other through said eccentric gears, and bearings for the shafts located on each side of each pair of eccentrics.

12. In a press, co-operating presser members relatively movable between work receiving and work pressing positions with respect to each other, means to cause such relative movements between the presser members comprising a power-driven shaft, an eccentric on the shaft, a countershaft carried by one of the presser members and arranged in parallelism with respect to the first-mentioned shaft, an eccentric carried by the countershaft in position to cooperate with the first-mentioned eccentric, means located substantially at the center of the countershaft to drive the latter from the power shaft whereby the eccentrics are caused to effect relative movement between the presser members, and bearings for the shafts located between said driving means and the pair of eccentrics and on each side of said driving means.

13. In a press, a stationary presser member, a presser member movable between work receiving and work pressing positions with respect to the stationary presser member, means to move the movable presser member comprising a power-driven shaft, an eccentric on the shaft, a countershaft mounted in the movable presser member and arranged in parallelism with respect to the first-mentioned shaft, an eccentric carried by the countershaft in position to co-operate with the first-mentioned eccentric, eccentric gears in mesh with each other and mounted fixedly on the shafts whereby the eccentrics are caused to effect movement of the movable presser member, and bearings for the shafts located between the eccentric and the eccentric gear on each shaft and also on each side of each eccentric and of each eccentric gear.

GUSTAV ADOLF SCHETTLER.
